CLAIM

The ornamental design for a shoe, as shown and described.

DESCRIPTION

FIG. 1 is a side view of the shoe showing my new design;

FIG. 2 is a top plan view thereof;

FIG. 3 is a rear elevation view thereof;

FIG. 4 is a front elevation view thereof; and,

FIG. 5 is a front perspective view thereof.

The broken lines showing the heel and sole are for illustrative purposes only, in order to complete the disclosure of the article in which the claim is embodied, and form no part of the claimed design.
